UNITED STATES PATENT OFFICE.

SILAS N. GALLUP, OF MACEDON, NEW YORK.

GEARING FOR CHANGING SPEED.

SPECIFICATION forming part of Letters Patent No. 295,536, dated March 25, 1884.

Application filed January 24, 1884. (No model.)

To all whom it may concern:

Be it known that I, SILAS N. GALLUP, of Macedon, county of Wayne, State of New York, have invented a new and useful Improvement 5 in Gearing for Changing Speed, of which the following is a full, clear, and exact description, reference being had to the accompanying drawings, making part of this specification.

My invention relates to an improved device 10 or gearing for changing speed, particularly designed for use upon seeding-machines and grain-drills, for varying the speed of the seed-distributing devices, and the quantity to be sown or planted upon a given area, as may be 15 desired, and it will therefore be described with reference to such application or use of it; but it will be apparent from the following description that its use need not be confined to the particular class of machines referred to, as it 20 may be readily adapted to other uses than that named.

It consists in the combination of two cone 25 gears or pulleys, one of which imparts motion to the other, and one of which, also, is adapted to be adjusted laterally, for varying the relation of one to the other, and one of which is mounted in adjustable boxes, for adapting it to be set nearer to or farther from the other, and a transmitting-pinion or equivalent means for 30 connecting said gears and communicating motion from one to the other; and in certain details of construction and arrangement of parts for facilitating their adjustment and change of speed, as hereinafter explained.

In the accompanying drawings, Figure 1 is 35 a perspective view of my improved gearing, showing also a portion of the grain-box of a seeding-machine, to which said gearing is applied. Fig. 2 is a rear elevation, partly in 40 section, with the pinion connecting the cone-gears removed. Fig. 3 is a similar view to Fig. 2, illustrating the lateral adjustment of one cone-gear relatively to the other. Fig. 4 is a perspective view, showing a modification 45 in which adjustable cone-pulleys are connected by an endless belt; and Figs. 5 and 6 are detail views, showing the joint in the pinion-supporting arm—one a vertical section through and the other a plan view of said joint.

A represents a portion of the grain box or 50 hopper of a seeding-machine, to the bottom of

which, at one end, are secured pendent angular brackets B B', in which the gear-shafts C, C', and C² have bearings. The shaft C, in practice, is the first or main driving-shaft of 55 the machine, on which the carrying and drive wheels are mounted, and in addition to its bearings in the hangers B B' will have also the usual bearings in the side frame-timbers of the machine.

Upon the shaft C is secured a cone-wheel, D, or, rather, a series of gears, d, d', and e, of 60 different diameters, arranged side by side, in such relation as to give them, as a whole, the conical form shown, and upon the shaft C' is secured a second cone-gear, E, similar to D, but in reversed position. These gears are located between the hangers B B', and the latter are sufficiently far apart to permit the lateral adjustment of the cone E, for varying the 65 relation of its gears to those of cone D, such lateral adjustment being effected by the longitudinal adjustment of the shaft C', as follows: The outer end of the shaft C' is provided with 70 series of annular grooves, or ribs, or collars c c, forming teeth which extend entirely around the shaft in parallel relation to each other, and the teeth k' of a quadrant formed on the lower end of the lever b, pivoted in a bracket, a, attached to the end of the hopper A, or other 75 suitable support, engage with said teeth c without interfering with the rotation of the shaft C'. The upper end of lever b engages with a rack, a', which holds said lever at any 80 desired adjustment. By vibrating the lever b 85 the shaft C' can be adjusted longitudinally in its bearings for moving the cone-wheel laterally as desired. The inner end of the shaft C' is grooved at c', and has a pinion, F, feathered to and turning with it, said pinion en- 90 gaging with and actuating a pinion, F', fast on the shaft C², which in practice constitutes the distributor-wheel shaft, said shaft connecting with and actuating the distributing-wheels of the machine in any usual or pre- 95 ferred manner.

The hanger B has a forked bracket, f, secured to it, the fork of which enters a groove, f', in the hub of pinion F, and serves to hold 100 said pinion in working relation to the pinion F' when the shaft C' and its cone-pulley E are adjusted as above described.

In suitable bearings on the horizontal arms of the brackets or hangers B and B' is mounted a rock-shaft, G, upon which, between said hangers, is rigidly secured a jointed arm, H H', the outer bifurcated portion, H', of which is provided in its outer end with bearings for a pinion, I, adapted to be interposed between said cone-gears D and E, for communicating motion from one to the other. The shaft G has teeth g g on its outer end, similar to the teeth c on the shaft C', and the teeth of a quadrant-lever, K, similar to lever b, above described, engage therewith, for effecting the longitudinal adjustment of said shaft G and the lateral adjustment of the arm H H' and pinion I, for adapting the latter to engage with any one of the gears d, d', and e of the cone D, for imparting motion through the gear of cone E in the same plane therewith to the shaft C'. By reference to Figs. 5 and 6 it will be seen that the joint between the parts H and H' of the arm in which the shaft of the pinion I has its bearings is so constructed as to limit the movement of the arm H in one direction. The end of arm H', connected with arm H, is bifurcated, or has short parallel ears h h, through which and the interlapping end of arm H a pin or bolt passes, uniting said ends, and the face or side of arm H has a wedge-shaped rib or piece, h', formed upon or secured to it, which serves to prevent the arm H from falling so low as to throw the pinion I out of working relation to the cone D. The wedge may be made separate from the arm H, and may be secured thereto by a screw passing through a longitudinal slot in the wedge, adapting it to be adjusted to vary the throw of the arm H' or to compensate for wear, as may be required. The direction of movement of cone D is indicated by the arrow in Fig. 1. When the pinion I is thrown into gear with any one of the gears of the cone D, the movement of the latter causes said pinion to immediately roll up into engagement with the opposing gear of cone E, for actuating through the latter the shaft C'. The lateral adjustment of the cone E, as above described, by bringing the gears of said cone into different relation to those of cone D, serves to add to the changes that may be made in the speed of shaft C', with a smaller number of different-sized gears on the cone than would otherwise be required, thereby reducing the cost of manufacture.

Where cone-pulleys are used, connected by an endless belt, L, as shown in Fig. 4, one of the shafts C and C' will be mounted in boxes M, adjustable in the hangers B, for setting the shafts nearer to each other or farther apart, for the purpose of accommodating the lateral adjustment of the cone E without necessitating the changing of the belt for one of greater or less length. The boxes M in this construction are movable in slots or ways in the brackets

B, and may be adjusted by set-screws m or 65 other suitable means for the purpose.

For changing the speed, the operator by grasping with one hand the pinion-arm H can rock the pinion I back out of engagement with the cone D, when by rocking the lever K the arms H H' will be moved laterally until the pinion I is brought over the desired gear of cone D; when it is allowed to fall into engagement therewith, and is immediately carried by the action of said gear into engagement with the opposing gear of cone E, and serves to actuate the latter in a manner that will be readily understood.

Where the shaft C' is mounted in adjustable boxes M, as above described, the lever b, for effecting the lateral adjustment, may be slotted, as shown at b², to adapt it to slide on its fulcrum-pin to accommodate such adjustment of the shaft.

Having now described my invention, I claim as new—

1. In a device for changing speed, the cones D and E, mounted upon parallel shafts, and having a lateral adjustment one relatively to the other, in combination with the laterally-adjustable pinion I, mounted in the jointed arm H H', arranged and operating substantially as described.

2. The combination of the cone-gears D and E, fast one on the driving-shaft C and the other on the driven shaft C', one of said shafts being longitudinally adjustable in its bearings, in combination with adjustable bearing-boxes for one of said shafts, and means for effecting the adjustment of said shafts and bearing-boxes, substantially as described.

3. The combination of the cones D and E, the sliding shaft C', the pinion F, feathered to and sliding on said shaft, and means for adjusting said shaft longitudinally in its bearings, substantially as described.

4. The pinion I, for communicating motion from the cone D to the cone E, and, in combination with said pinion and cones, the jointed arm H H', provided with the knuckle or rib for limiting the movement of the part H' of said arm, rock-shaft G, to which said arm is secured, and means for adjusting said shaft and arm, all substantially as described.

5. The combination of the shafts C and C', the cones D and E, the latter adjustable laterally with its shaft, the pinion F, feathered to and sliding on the shaft C', means for adjusting said shaft C' and its cone laterally, the connecting-pinion I, and means for adjusting the latter, all substantially as and for the purpose described.

In testimony whereof I have hereunto set my hand this 21st day of January, A. D. 1884.

SILAS N. GALLUP.
